UNITED STATES PATENT OFFICE

HARRY E. HOUGHTON, OF BRONXVILLE, NEW YORK, ASSIGNOR TO HOOKLESS FASTENER COMPANY, OF MEADVILLE, PENNSYLVANIA, A CORPORATION OF PENNSYLVANIA

DESIGN FOR A PULL FOR A SLIDE FASTENER

Application filed February 27, 1932. Serial No. 43,021. Term of patent 14 years.

To all whom it may concern:

Be it known that I, HARRY E. HOUGHTON, a subject of Great Britain, residing at Bronxville, in the county of Westchester and State of New York, have invented a new, original, and ornamental Design for a Pull for Slide Fastener, of which the following is a specification, reference being had to the accompanying drawing, forming a part thereof.

In the drawing:

Fig. 1 is a plan view of a pull for a slide

fastener, illustrated as applied to a slider and showing my new design.

Fig. 2 is a side view of the pull, the slider being shown in dotted lines.

Fig. 3 is an end view of the pull, the slider shown in dotted lines.

I claim:

The ornamental design for a pull for a slide fastener substantially as shown.

In testimony whereof I affix my signature.

H. E. HOUGHTON.
